SHOE FLEXING DEVICE

Edward R. Byers, Williams, Ariz.

Application April 17, 1935, Serial No. 16,874

3 Claims. (Cl. 12—17)

The present invention relates to new and useful improvements in shoe flexing devices and has for its primary object to provide a machine for "breaking in" pairs of shoes, said machine embodying a novel construction, combination and arrangement of parts through the medium of which the shoes may be subjected to substantially the same flexings and manipulations which occur when being worn on the feet.

Another very important object of the invention is to provide a shoe flexing machine of the aforementioned character which is adapted for various sizes of shoes.

Other objects of the invention are to provide a shoe flexing device of the character described which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in front elevation of a shoe flexing device or machine construction in accordance with the present invention.

Figure 2 is a vertical sectional view, taken substantially on the line 2—2 of Figure 1.

Figure 3 is a detail view in top plan of one of the forms or lasts.

Figure 4 is a view in vertical longitudinal section through one of the forms or lasts.

Figure 5 is a view in vertical transverse section through one of the forms or lasts, taken substantially on the line 5—5 of Figure 3.

Referring now to the drawings in detail, it will be seen that the embodiment of the invention which has been illustrated comprises a frame 1 having journaled transversely therein front and rear shafts 2 and 3, respectively. A chain and sprocket connection 4 couples the front shaft 2 to an electric motor (not shown) or other suitable source of power for actuation thereby. A chain and sprocket connection 5 couples the shafts 2 and 3 for operation in unison. Pairs of eccentrics 6 and 7 are fixed on the shafts 2 and 3, respectively.

As best seen in Figure 2 of the drawings, the frame 1 has formed in opposite sides thereof slots 8. Mounted for adjustment in the slots 8 is a transverse rod 9 which is secured in adjusted

position through the medium of wing nuts 10.

Mounted for swinging movement in a vertical plane on the rod 9 are front and rear plates 11 and 12, respectively, which rest on the eccentrics 6 and 7 and are actuated thereby. The front plate 11 is longitudinally split or slotted to accommodate 5 the drive chain 4, a guard 13 being provided on said plate 11 for said chain.

The shoes 14 to be broken in are placed in position with the heels thereof resting on the rear end portion of the plate 12 and the ball portions 10 thereof resting on the front plate 11 at a point adjacent the hinge rod 9, as illustrated to advantage in Figure 2 of the drawings. The reference numeral 15 designates generally flexible and adjustable rubber lasts to be mounted in the 15 shoes 14 before said shoes are placed in the machine. The lasts 15 have formed in the rear portions thereof sockets 16 (see Figure 3) for the reception of upstanding shanks 17. Each last 15 includes a pair of complementary half sections 18 20 of rubber having a steel spring 19 embedded therein and exposed at the opposed inner walls of said half sections, as seen in Figures 4 and 5. Complementary tapered half nuts 20 are welded on the steel springs 19 in the half sections 18 for 25 threadedly receiving a tapered adjusting screw 21. The adjusting screw 21 is provided with a slot 22 for the reception of a screw driver or other suitable tool. The opposed walls of the half sections 18 have formed therein complementary 30 grooves 23 which, in conjunction with each other, define a socket in which the adjusting screw 21 is operable. The half sections 18 are connected to each other for lateral adjustment in any suitable manner, as at 24.

The supporting structure or frame 1 includes an arch 25 and welded in the top portion thereof are nuts 26 (see Figure 2) in which pressure screws 27 are threadedly mounted, said pressure screws extending through the frame and being 40 provided, on their upper ends, with operating wheels 28. Metallic casings 29 are also fixed, as by welding, in the top portion of the frame and depend therefrom, said casings enclosing the nuts 26. Swivelly mounted on the lower ends of the 45 pressure screws 27 are socketed heads 30 which are operable in the casings 29. Pistons 31 are also slidably mounted in the casings 29, said pistons having substantially convex lower ends engageable in the substantially concave upper ends of 50 the shanks 17. Coil springs 32 are interposed between the heads 30 and the pistons 31, said coil springs being fixed, as by welding, at their ends to the elements 30 and 31.

It is believed that the operation of the machine 55

will be readily apparent from a consideration of the foregoing. The shoes to be broken in, with the lasts 15 therein, are positioned on the plates 11 and 12, the pistons 31 are engaged with the shanks 17, and the desired pressure is then applied through the medium of the screws 27. The electric motor or other source of power is then started for driving the shafts 2 and 3 on which the eccentrics 6 and 7 are fixed, thus actuating the plates 11 and 12 in a vertical plane for flexing the shoes in a manner closely simulating the treatment to which shoes are ordinarily subjected when walking.

It is believed that the many advantages of a shoe flexing machine constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed.

What is claimed is:—

1. A shoe flexing machine comprising a frame, a rod mounted on the frame, plates journaled on the rod for swinging movement in the vertical plane and projecting in opposite directions from said rod, means for actuating the plates, and means for securing shoes on the plates under pressure, the last-named means including lasts mounted in the shoes, shanks rising from the lasts, pressure screws threadedly mounted in the frame, casings mounted on the frame, pistons

operable in the casings and engageable with the shanks, and resilient means operatively connecting the pistons to the pressure screws for actuation thereby.

2. A shoe flexing machine comprising a frame, a rod adjustably mounted on said frame, plates journaled for swinging movement in a vertical plane on the rod and extending in opposite directions therefrom, shafts journaled in the frame, eccentrics on the shafts engaged beneath the plates for actuating said plates, means for actuating the shafts in unison, and means for securing shoes in position on the plates.

3. A shoe flexing machine comprising a frame, a rod adjustably mounted on said frame, plates journaled for swinging movement in a vertical plane on the rod and extending in opposite directions therefrom, shafts journaled in the frame, eccentrics on the shafts engaged beneath the plates for actuating said plates, means for actuating the shafts in unison, and means for securing shoes in position on the plates, the last-named means including resilient lasts engageable in the shoes, shank rising from the lasts, nuts fixed on the frame, substantially tubular casings fixed on the frame and depending therefrom, said casings enclosing the nuts, pressure screws threadedly mounted in the nuts, heads swivelly mounted on the pressure screws and operable in the casings, pistons operable in the casings and engageable with the shanks, and coil springs connecting the pistons to the heads for actuation thereby.

EDWARD R. BYERS.
